UNITED STATES PATENT OFFICE.

MATTHEW M. BROWN, OF ERIE, PENNSYLVANIA.

CURRENT MOTOR.

Application filed April 19, 1923. Serial No. 633,055.

The purpose of the invention is to utilize water current for generating power. In carrying out the invention I utilize a rotary carrier preferably in the form of a belt operating on cylinders sufficiently buoyant to float. Arranged on this carrier are a series of blades which swing to the perpendicular position at the underside of the carrier and are permitted to fold up on the return, or upper side of the carrier. Ordinarily the device will be anchored so that the return movement of the blades will be well below the surface of the water but under certain conditions the whole device may be anchored to operate at the surface.

The invention is illustrated in the accompanying drawings as follows:

Fig. 1 shows a longitudinal section of the device.

Fig. 2 a longitudinal section of one of the blades in folded position.

Fig. 3 an enlarged view of the blade showing the means of securing the limiting means.

Fig. 4 a section on the line 4—4 in Fig. 3.

Fig. 5 an enlarged longitudinal section of a part of the carrier.

Fig. 6 a plan view of one end of the carrier, partly in section.

Fig. 7 an enlarged cross section of the carrier.

Fig. 8 a plan view of an alternative construction.

Fig. 9 an end view of the same.

Fig. 10 an enlarged cross section of a part of the carrier on the line 10—10 in Fig. 8.

Fig. 11 a section on the line 11—11 in Fig. 9.

Fig. 12 an enlarged section on the line 12—12 in Fig. 8.

1 in the preferred construction marks the belt, and 2 and 3 cylinders over which the belt operates. Ordinarily these cylinders will be formed of logs and the logs and carrier will be sufficiently buoyant to float.

Anchor cables 5 operate on rings 4 secured on the cylinders, the rings 4 having grooves for receiving the cables. The rear ends of the cables are carried by anchor shackles 6

50 in the anchors 7, the anchors 7 being any convenient anchoring for the purpose. The belt 1 is made up of a series of cross members 8 of wood having openings through which cables 9 extend. At intervals cross

55 pieces 10 formed of channel iron alternate

with the wood members, these having openings 11 through which the cables extend. The channel is filled by a wood member 10^a. The carrier, as a whole is buoyant and is preferably anchored as shown in Fig. 1, 60 above the ground level B and below the surface level of the water A, it being dependent upon the buoyancy for maintaining the apparatus off the bottom and the anchoring devices preventing the apparatus from rising to the surface. The current tends to maintain the apparatus and the carrier on a level with the anchor, the buoyancy tending to lift the apparatus above this level and the current tending to maintain the alignment.

65 Hinge lugs 12 are welded or secured to the channels 10. Pintles 13 extend through these lugs and blades 14 are hinged on the pintles 13 by means of straps 15 which extend around the pintles and along the sides of the blades 14. The straps 15 are secured to the blades by rivets 16.

70 Spools 17 are fixed on the pintles between the straps 15 and links 17^a are secured on the spools 17. Chains 18 extend from the links 17^a to a link 19. The link 19 extends through openings 20 in the blade and has its ends bent over and re-enforcing the plate 21 on the opposite side.

75 The chains 18 are of a length to limit the swinging movement of the blades on the hinge to a perpendicular position relatively to the carrier in one direction and to permit the folding down of the blades on the carrier 80 when swung to the opposite direction. As shown in Fig. 1 it will be seen that the blades assume this perpendicular position at the bottom of the carrier and are locked against any forward movement by the chains, the 85 bottom of the carrier moving in the direction of the arrow. As the carrier reaches the cylinder 2 the blades fold on the carrier and pass along the upper part in the folded position. This is desirable when the device is floating on the surface and essential when the device is submerged.

90 In the alternative construction a single cylinder 24 is used. This is anchored by cables 5 in the same manner as the preferred construction. A series of bands 25 extend around the cylinder 24 and pintle rods 26 extend through these bands forming hinge pintles for the blades 27. Straps 28 extend 95 around the rods and along the sides of the 100

110 pieces 10 formed of channel iron alternate

blades and are secured to the blades by rivets 29. Spools 30 are arranged on the pintle rods 26. Links 31 are carried by these spools. Chains 32 extend from the links 31 and are secured at 33 to the blades 27. Drive wheels 34 are mounted on the cylinder 24 and power is transmitted from the device by a cable 35.

The operation of this device can be readily understood. As the blades descend into 10 the current they assume a radial position, the movement being limited by the straightening of the chains 32. The blades fold on the cylinder as they pass up and back over the top. Thus the device while operable 15 floating at the surface is ordinarily operable when submerged. This ability to operate submerged permits the device to be used where ice or other conditions make surface operation undesirable.

20 It will be noted that while I have shown this with the blades operating on the bottom reach of the carrier if by reason of shallow water, or otherwise, it is desirable to make the power side of the carrier on top the blades 25 can be locked against the down current side

on top instead of on the bottom and fold on the bottom.

What I claim as new is:—

1. In a current motor, the combination of a rotary carrier; current opposing blades; 30 a hinge comprising a pintle for swingingly mounting each of the blades on the carrier; and means limiting the swinging of the blades in one direction and permitting the folding of the blades on the carrier by swinging in the opposite direction comprising a flexible connection; spools on the hinge pintle; links on the spools anchoring the connections; and means for securing the connections to the next advance blade. 35

2. In a current motor, the combination of a rotary buoyant carrier; means on the carrier acting under the influence of the current rotating the carrier; and anchors retaining the carrier against its buoyancy below the 40 surface and permitting the carrier through its buoyancy to rise above the bottom. 45

In testimony whereof I have hereunto set my hand,

MATTHEW M. BROWN.
